Primary Examiner — Stacia A Cadmus(74) *Attorney, Agent, or Firm* — Renner, Otto, Boisselle & Sklar, LLP(57) **CLAIM**

The ornamental design for a wheel or wheel cover, as shown and described.

DESCRIPTIONFIG. 1 is a perspective view of a wheel or wheel cover according to the design; and,
FIG. 2 is a front view thereof.

The broken lines in the drawings illustrate environmental subject matter only and form no part of the claimed design.

1 Claim, 2 Drawing SheetsFIG. 1

FIG. 2
